UNITED STATES PATENT OFFICE.

JOHN B. COFFEY AND SAM F. COFFEY, OF NASHVILLE, TENNESSEE.

VENDING MACHINE.

Application filed January 8, 1925. Serial No. 1,274.

The present invention relates to vending mechanism and provides an attachment to be associated with a fluid dispensing pump such as generally provided for gasoline stations so that upon depositing a coin of predetermined denominative value a given amount of fuel or oil may be obtained.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a side view of a vending mechanism embodying the invention,

Figure 2 is an enlarged sectional view thereof,

Figure 3 is a detail sectional view on the line 3—3 of Figure 2,

Figure 4 is a detail sectional view on the line 4—4 of Figure 2, and

Figure 5 is a detail sectional view on the line 5—5 of Figure 2.

Corresponding and like parts are referred to in the following description and designated in the several views of the drawings by like reference characters.

The numeral 10 denotes a suitable housing for enclosing the operating parts. A transverse shaft 11 is journaled in opposite sides of the housing 10 and projects at one end to which is fitted a gear wheel 12 which is arranged to cooperate with the pump operating rack 13. A detent wheel 14 and a gear wheel 15 are mounted upon the shaft 11 and are secured thereto so as to rotate therewith. A double ended dog or detent 16 coacts at its respective ends 16^a and 16^b with the detent wheel 14 to prevent rotation thereof and operation of the vending mechanism, the end 16^b being connected by means of a link 17 with one arm of a lever 18 the other arm of said lever being disposed to coact with a rack bar 19, the teeth of which are adapted to mesh with the teeth of the gear wheel 15, said rack bar being held in predetermined position by rollers 20 which are adjustable to maintain proper meshing relation of the teeth of the rack bar 19 and gear wheel 15. A latch 21 is adapted to engage one end of the

lever 18 so as to hold the detent 16 in neutral position as indicated by the dotted lines in Figure 2, whereby the mechanism may be operated at will without necessitating the deposition of a coin. A rod 22 at one side of the rack bar 19 and connected thereto is provided with an upper stop 23 and a lower stop 24, said stops being adjustable. The upper stop 23 is adapted to engage one end of the lever 18 and the lower stop 24 is adapted to engage one end of a lever 25 which is connected by means of a link 26 with an arm 27, which in turn is connected by means of a link 28 with a cut off 29 adapted when lowered to extend across the entrance of a coin chute 30. A spring 31 normally tends to close the cut off 29. A passage 32 opens into a coin box 33 and the coin chute 30 is in communication therewith and this passage receives a plunger 34 which is normally held at the limit of its outward movement by means of a spring 35. A retarder 36 normally projects into the passage 32 and is adjustably connected to the detent 16 and operates to retard the forward movement of a coin 37 when entering the passage after leaving the coin chute 30.

The operation of the machine is as follows:

Normally the rack bars 13 and 19 are in lowered position and the cut off 29 is held elevated by the stop 24 engaging the adjacent end of the lever 25. Operation of the mechanism is prevented by the detent 16 at end 16^b engaging a tooth of the detent wheel 14. Upon depositing a coin 37 in the chute 30 it is received in the passage 32, its forward movement being checked by the retarder 36. The plunger 34 being pressed inwardly causes the coin 37 to ride under the retarder 36 with the result that the detent 16 at end 16^b is moved away from the teeth of the detent wheel 14 and is held in such position by means of a spring 38 mounted upon a stem 39 consisting of separate sections 39' and 39'' connected by said spring, the latter section being pivoted at one end to the housing as indicated at 40 and the former being pivoted at 40' to the stem 41 of the detent 16. When the stems 39 and 41 are in line, the detent is in neutral position or upon the dead center and a slight movement in either direction causes the spring 38 to react and throw the detent end 16^a or 16^b into engagement with the detent wheel 14. The cut-off 29 is withdrawn from chute 30 when the rack bars are in their normal or lowered position

and lug 24 is engaging lever 25. In that case ordinarily upper end 16^b would be engaging wheel 14 so that wheel 14 could not be turned clockwise in Figure 2. If a coin is then inserted and plunger 34 operated, the lower end 16^a would be thrown into engagement with wheel 14 while the upper end 16^b would move away from wheel 14. However, cut-off 29 would still be withdrawn until the handle was turned clockwise whereupon rack 19 would ascend, lug 24 would move out of engagement with lever 25, and spring 31 would cause cut-off 29 to enter the chute 30. When the coin engages part 36, end 16^a engages the teeth and rides over the teeth as wheel 14 is turned clockwise. When member 23 engages lever 18, end 16^b is thrown into engagement with the teeth and rides over the teeth as wheel 14 is turned in the opposite direction. The detent 16 remains in neutral position only when so held by hook 21 when it is desired to operate the device without a coin. When the detent 16 at its end 16^b is in engagement with wheel 14, the pump may be operated to discharge the required amount of fuel or oil and during this operation the rack bars 13 and 19 are elevated and when at the limit of their upward movement the stop 23 operates the lever 18 to throw the detent at end 16^b into locking engagement with wheel

14 to prevent operation thereof until another coin is deposited, and when the rack bars return to normal positions the locking engagement of end 16^b and wheel 14 is not disturbed but the stop 24 operates the lever 25 and elevates the cut off 29 to admit of another coin being deposited in the coin chute 30 for the next operation of the vending mechanism.

What is claimed is:—

In a machine of the class described, means to operate the same, including a toothed wheel and a gear member, a pivoted dog provided with two projections, one projection normally engaging with the toothed wheel, coin controlled means for operating the dog so as to disengage said first mentioned projection from the toothed wheel, a connection for the dog consisting of pivoted parts and including a spring to maintain one or the other of said projections in engagement with the toothed wheel, a lever, a connection between said first mentioned projection and said lever, and an operating member driven by said gear member for engaging the lever so as to cause said first mentioned projection to engage the toothed wheel.

In testimony whereof, we affix our signatures.

JOHN B. COFFEY.
SAM F. COFFEY.
